UNITED STATES PATENT OFFICE.

ARTHUR D. VANDERGON, OF MAPLE LAKE, MINNESOTA.

SUCTION-CURRYCOMB.

1,149,481.

Specification of Letters Patent. Patented Aug. 10, 1915.

Application filed March 17, 1914. Serial No. 825,364.

To all whom it may concern:

Be it known that I, ARTHUR D. VANDERGON, a citizen of the United States, residing at Maple Lake, in the county of Wright and State of Minnesota, have invented certain new and useful Improvements in Suction-Currycombs, of which the following is a specification.

This invention relates to a suction curry comb, and the principal object of the invention is to provide a curry comb including a cleaning element, means for rotating the cleaning element, and suction elements including a tube surrounding the means for rotating the cleaning element so that as the horse's coat is cleaned, the dust will be sucked through the tube and deposited in a suitable receptacle.

This invention is illustrated in the accompanying drawings wherein—

Figure 1 is a view of the suction cleaner shown in elevation; Fig. 2 is an end view of the cleaning element; Fig. 3 is a sectional view through the cleaning element; Fig. 4 is a sectional view taken along the line 4—4 of Fig. 1; Fig. 5 is a transverse sectional view through the suction housing; Fig. 6 is an enlarged view of one of the links of the flexible shaft which connects the driving shaft with the cleaning element; Fig. 7 is a transverse sectional view through the suction tube taken along the line 7—7 of Fig. 4.

The gear housing 10 is supported above the base 11 by means of the standards or braces 12 and carries the large bevel gear 13 which is mounted in the main section of the gear housing and the small bevel gear 14 which is mounted in the arm 15 of the housing. The main driving gear 13 is rigidly mounted upon the spindle 16 which extends beyond the gear housing and carries the crank 17. It is, of course, obvious that the crank would only be used in case the spindle 16 is to be rotated by manual power and that the crank 17 may be done away with and any other means provided for rotating the spindle 16. This would permit the spindle 16 to be driven from a suitable motor.

The driven shaft 18 has one end extending into the arm or extension 15 of the gear housing 10 and has the small bevel gear 14 rigidly mounted upon its inner end so that when the gear 14 is rotated by the large bevel gear 13, the driven shaft 18 will be rapidly rotated. This driven shaft 18 ex-

tends into a fan housing 19 which is supported above the base 11 by means of the collar 20 and carries a fan 21 which has its blades so pitched that when the shaft 18 is rotated, air will be sucked out of the fan 60 housing 19. The forward end portion 22 of the fan housing is tapered and terminates in an inlet opening through which the driven shaft 18 projects.

The suction tube 23 leads from the inlet 65 of the fan housing 19. This suction tube is formed of inner and outer layers 24 and 25 which are formed of any suitable material which will be airtight, the preferred construction being similar to the construction 70 of a hose pipe. Within the layer 25 there is provided a spiral coil 26 formed of a strip of resilient material, such as sheet metal, the coil resembling a spring and serving to hold the suction tube in a distended condition and preventing the tube from doubling or getting twisted and getting out of shape. It will thus be seen that the coil will hold the suction tube in the proper shape and prevent the tube from being cracked or being doubled a sufficient amount to shut off the passage of air through the tube. 75

A flexible cable 27 extends through the suction tube 23 and has its inner end connected with the driven shaft 18 and its outer end 80 connected with the spindle 28. This flexible shaft 27 is formed from links shown in Fig. 6. Each of these links is formed from a strip of rod metal and is bent to form a bar 29, and eyes 30, the ends 31 of the rod being 85 twisted about the bar 29. This construction forms a very strong link which will not easily bend out of shape and which will not easily jam or become twisted apart.

The spindle 28 is rotatably mounted in the 90 bearing 32 which is supported by arms 32' in the housing 33 and fits into the square 34 formed in the hub 35 and will be rotated when the flexible shaft is rotated. Spokes 36 extend from the hub 35 and carry the 100 bands 37 which may be provided with smooth edges or with teeth similar to those found in the cleaning strips of ordinary curry combs. The side wall 38 of housing 105 33 is formed of rubber or some other flexible material such as heavy leather so that the side wall may give a sufficient amount to permit the cleaning bands 37 to engage the coat of the horse and cleaning the same. 110 It should also be noted that by having the

wall formed of flexible material, there is no danger of the skin being scraped, thus causing sores to be formed.

When using this curry comb, the driving spindle 16 will be rotated either by the crank or a suitable motor connected with the same. As the driving spindle 16 rotates, rotary motion will be transmitted to the driven shaft 18 and this will rotate the flexible shaft 27. The flexible shaft will rotate the cleaning element shown in Figs. 2 and 3 and the fan 21 will cause a suction through the suction pipe 23 so that dust and dirt scraped from the horse's coat by the cleaning element will be sucked into the suction tube and into the fan housing 19 from which it will be driven by the fan. It is not necessary to place a receptacle about the open end of the fan housing since the fan housing and driving mechanism could be placed outside the building in which the horses are cleaned and the dust and dirt would thus be driven into the open air. By having the cleaning strips 37 shaped as shown in Fig. 2, the strips will move across the horse's coat with a diagonal sliding motion instead of with a straight scraping motion and therefore the horse's coat will be very thoroughly cleaned. It should be noted that if the cleaning strips become worn out the cleaning element can be removed from the spindle 28 and a new spindle put in place. It should be also noted that this cleaning element is made removable so that a set of cleaning elements may be provided and changed according to

the needs of the horse's coat which is being cleaned, that is to say, a curry comb having cleaning strips of one type could be substituted for the one in use or the curry comb in use can be removed and the brush substituted for the curry comb.

What is claimed is:

1. A cleaner of the character described comprising a housing having a central bearing, a spindle rotatably mounted in said bearing, a hub mounted upon said spindle within said housing, spokes extending from said hub, elliptical bands carried by said spokes, and means for rotating said spindle. 45

2. A cleaning device of the character described comprising a housing provided with a central bearing, flexible side walls forming part of said housing, a spindle rotatably mounted in said bearing, a hub carried by 55 said spindle within said bearing, spokes extending from said hub, cleaning bands carried by said spokes, and means for rotating said spindle.

3. A cleaner of the character described 60 comprising a housing, a spindle rotatably mounted in said housing, carrying means in said housing rotating with said spindle, elliptically arranged operating means carried by said carrying means, and means for 65 rotating said spindle.

In testimony whereof I affix my signature in presence of two witnesses.

ARTHUR D. VANDERGON.
